UNITED STATES PATENT OFFICE

SOLOMON PEARCE, OF ELIZABETH, ILLINOIS

HAYRACK

Application filed November 19, 1929. Serial No. 408,350.

This invention relates to hay racks and, more particularly, to what are known as basket hay racks as applied to wagons. Among other objects, it aims to provide an improved 5 self-locking connection between the side frame members of the wagon and the platform whereby a strong and very durable connection is made and whereby the parts may be assembled and dismantled very readily.

10 In the accompanying drawing, wherein there is shown a selected embodiment of the invention:

Fig. 1 is a cross sectional view of a hay rack embodying the improvements;

15 Fig. 2 is a fragmentary sectional view showing interlocking connection between the wagon platform and one of the standards of a side frame;

Fig. 3 is a sectional view taken on the line 20 3—3 of Fig. 2; and

Fig. 4 is a sectional view similar to Fig. 2, but showing one side frame removed.

Referring particularly to the drawing there is shown a hay rack for a wagon including 25 a flat platform 10 mounted on the usual cross beams or arms 11 which are spaced at intervals on the longitudinal sills or frame members 12.

At the opposite sides of the platform 10, 30 there are shown a pair of side frames each made of a series of uprights or standards 13 to which longitudinal side slats or boards 14 are connected. My improvements relate particularly to the manner of connecting and 35 supporting these side frame members on the flat platform so that they can be quickly removed or set in place and will not become dislodged or fall off when the hay rack is loaded.

40 Herein, referring to Figs. 1 and 2, the standards or certain of the standards 13 of the side frames are arranged to be seated on the side rails 15 of the platform immediately above the cross beams 11 and hook-shaped 45 locking members 16 are shown as being bolted to these standards so that the bent ends of the hook-shaped members lie slightly above the top of the platform. It will be observed that the side rails 15 in this example are somewhat thicker than the boards 10 composing

the bottom of the rack. Adjacent to the inside edges of the side rails 15 and loosely connected to the cross beams 11 are loop-shaped locking links or members 17 so arranged as to be engaged by the hook members 16. Referring to Figs. 2, 3 and 4, the loop-shaped members which resemble the links of a chain are each shown as working in a kerf or slot 18 cut in the cross members and preferably having a thin sheet of metal 19 affording a bearing surface for the bottoms of the links when they are pulled up as shown. A bridge plate 20 is preferably screwed across or at the bottom of each slot or kerf slot 18 so as to prevent the links from dropping down out of reach of an operator standing on the wagon platform, the idea being to permit him to lift the links or loops so that they may be engaged by the hook members, the side frames being held at such an angle to the platform that the ends of hooks 16 may engage the upper ends of the loops 17.

It will be seen that the side frames are adapted to be set up on the platform and are held or braced in their vertical position by means of braces 21 conveniently made of bent strap iron or steel. In this example, the braces have openings in which are inserted pins 22 arranged both on the standards 13 and the cross beams 11 and they are prevented from sliding or losing off the pins by any suitable means such as cotter pins, nuts or the like.

In order to remove the side frames in case it is desired to use the flat platform without them, it is only necessary to disengage the braces at one of their ends and swing the side frames inwardly over the flat platform thus automatically disengaging the hooks from the loops so that the side frames are free and can be lifted. When this is done, the loops 17 fall by gravity to the bottoms of their kerfs or slots and are entirely out of the way of any load that may be placed on the platform. This position of one of the links is clearly shown in Fig. 4.

From the foregoing description, it will be seen that the improved connections between the side frame members and the wagon or rack platform can be made very cheaply and

that the connections are absolutely rigid and secure when the brace members are attached. Furthermore, the frame members can be quickly applied to or removed from the platform or rack. There are no complex parts 5 that are apt to break and require replacement. All of the connections are made of steel, which may be drop-forged or rolled or die-stamped, and they will last as long, if not 10 longer, than the wood parts of the rack.

Obviously, the present invention is not restricted to the particular embodiment there-of herein shown and described.

What is claimed is:

15 1. A rack of the character described, comprising in combination, cross beams supporting a platform; side frame members presenting standards adapted to be set on the platform above the cross beams; hook-shaped 20 members secured to the inside edges of the standards adjacent to their lower ends; loop-shaped locking links loosely and slidably secured to said cross beams and projecting upwardly through said platform and engaging 25 said hook members; said cross beams presenting kerfs on the under sides of substantial depth to receive said links; metal bearing seats in the bottoms of said kerfs; and bridge plates across said kerfs arranged to 30 prevent the links from falling out of reach through the platform.

2. In a rack of the character described, in combination, cross beams supporting a platform; side frame members presenting standards adapted to be set on the platform; hook-shaped members secured to the inside edges of the standards adjacent to their lower ends; loop-shaped locking links loosely and slidably secured to said cross beams and movable 40 vertically in kerfs on the under sides of said cross beams; and means mounted on the cross beams and engaging said locking links when in their lowermost positions to hold the upper ends of said locking links slightly 45 spaced above the top surface of the platform, so that said links may be readily grasped by the fingers of an operator and lifted upwardly for engagement with the hook-shaped members, said links gravitating 50 into non-obstructive positions when disengaged from the hook-shaped members.

In testimony, that I claim the foregoing as my own, I have hereto affixed my signature.

SOLOMON PEARCE.
